UNITED STATES PATENT OFFICE.

JOSEPH A. REECE, OF TOLEDO, OHIO, ASSIGNOR TO THE LIBBEY-OWENS SHEET GLASS COMPANY, OF TOLEDO, OHIO, A CORPORATION OF OHIO.

BENDING ROLLER FOR DRAWN SHEET GLASS.

Application filed February 4, 1924. Serial No. 690,390.

To all whom it may concern:

Be it known that I, JOSEPH A. REECE, a citizen of the United States, residing at Toledo, in the county of Lucas and State of Ohio, have invented new and useful Improvements in Bending Rollers for Drawn Sheet Glass, of which the following is a specification.

This invention relates to improvements in the art of drawing sheet glass, and more particularly to an improved form of bending roller about which the plastic glass sheet is deflected from one plane into another.

15 In the system of drawing sheet glass disclosed in the patent to Colburn, 1,248,809, granted December 4, 1917, a sheet of glass is drawn vertically upward from a shallow pool of molten glass, and then while still 20 plastic is bent about a cylindrical roller into the horizontal plane where it is flattened and carried away through a leer as a continuous strip or ribbon of glass. In order to continuously maintain the width 25 of the sheet, and otherwise improve the quality of sheet produced, each edge of the sheet directly above the molten source passes between a pair of cooled, knurled, rollers, which are positively driven at a peripheral 30 speed considerably less than the linear speed at which the sheet is drawn upward. These cooled rollers grip and hold back on the edge portions of the sheet, and serve to stiffen and place an added tension on these 35 edge portions, the result being to keep the sheet to a uniform width. The edge portions of the sheet of glass will be roughened and somewhat thicker than the main central portion which will have smooth highly 40 polished surfaces and be of a uniform thickness.

Since the edge portions of the sheet are initially retarded by the knurled rollers, the different portions of the sheet will 45 travel at different speeds in their vertical run up to the bending roller. All portions of the sheet should pass around the the roller at about the same linear speed, but in order to attain this speed the cooled 50 edge portions, which are given a delayed start, must travel faster than the central portion during this vertical run. Due to this initial variation in speeds between the edge portions and the central portion of 55 the sheet, and the fact that the edge por-

tions are cooler and usually thicker than the central portion, there will sometimes be a difference in linear speed between the edges and the central portion while the sheet is passing about the bending roller. 60 This will necessitate slippage of some portions of the sheet on the roller surface and there will consequently be a liability of scratching or wrinkling the sheet during 65 this bending operation.

According to the present invention that portion of the bending roller which carries the main central portion of the sheet is made in the form of a freely rotatable sleeve set into the body of the bending 70 roll proper. The edge portions of the sheet are supported by, and in driving contact with, fixed cylindrical portions of the roll at the two ends of the central sleeve. Thus, the central portion of the sheet is allowed 75 to proceed at a somewhat different rate than the edge portions, during the bending operation. This will relieve the sheet from any undue strains at this point and will greatly diminish or eliminate the scratching and wrinkling of the sheet referred to above. 80

The objects and advantages of the invention will be better understood from the following detailed description of certain approved forms of the apparatus. 85

In the accompanying drawings:

Fig. 1 is an elevation of that portion of the sheet-drawing mechanism comprising the improved bending roller, the receptacle for 90 the pool of molten glass being shown in transverse vertical section.

Fig. 2 is a central vertical section on an enlarged scale through the bending member.

Fig. 3 is an elevation of one end of the 95 roller, showing auxiliary driving rollers co-operating with the fixed end portions of the bending roll.

The glass sheet 1 is drawn upwardly from the pool of molten glass 2 in receptacle 3. 100 After the sheet has been drawn upwardly till it has assumed approximately its final sheet form, but is still somewhat plastic, it is bent about the bending roller 4 into the horizontal plane. The sheet is then drawn 105 away through suitable drawing and flattening mechanism and thence into the annealing leer. The drawing and flattening mechanism is not here illustrated, but may be of the type disclosed in the Colburn pat- 110

ent referred to hereinabove. Each edge of the sheet adjacent its source passes between a pair of knurled or roughened rollers indicated at 5. These rollers are internally cooled, and are slowly driven at a peripheral speed considerably less than the linear speed at which the sheet is drawn upwardly. These rollers and the driving mechanism therefor, are described more in detail in the 5 Colburn patent referred to above. The edge portions 6 of sheet 1 will be marred or roughened by the gripping action of rollers 5, but these edges are eventually cut away and discarded. These edge portions 15 6 will draw somewhat thicker than the main body portion of sheet 1 and will be cooler and stiffer due to the contact therewith of the internally cooled rollers 5.

The central portion of the bending roll 20 4 is reduced in diameter as at 7, and mounted on this reduced portion is a cylindrical sleeve 8, having the same outer diameter as the end portions of bending roll 4. This sleeve 8 is made of some suitable alloy such 25 as Monel metal or nichrome, capable of taking and maintaining a high polish on its outer cylindrical sheet-supporting surface 9. The main portion of the bending roll 4 may be constructed in two sections screwed 30 together as at 10 to permit the insertion of the sleeve 8 upon the reduced portion 7 of the roller. Preferably roller bearings such as indicated at 11 will be used between the sleeve 8 and the portion 7 of the bending 35 roll on which it is mounted. The portions of the bending roll 4 adjacent either end of sleeve 8 are grooved or knurled as indicated at 12 to positively grip the roughened edge portions 6 of the glass sheet and hold the sheet against lateral contraction while 40 passing around the bending member.

While means are usually provided to drive the roller 4 to assist in beginning the sheet-drawing operation, ordinarily this roller 4 turns idly in roller bearings when the drawing operation is once under way. The roller 4 will then be rotated by the thickened edge portions 6 of the sheet which engage with the grooved ends 12 of the roller. Since the sleeve 8 which carries the main central portion of glass sheet 1 is freely rotatable with relation to the end portions 50 12 of roller 4, this central portion of the sheet will be allowed to rotate either faster or slower than the edge portions, thus relieving the sheet from any undue strains and eliminating the necessity for slippage of the fire-polished sheet surfaces upon the sheet-carrying surface 9 of the roller.

55 If the bending member 4 is to be used as a positive drawing member in lifting the sheet from its molten source, auxiliary driven rolls 13 will preferably be added. These rollers, which are mounted on a driven shaft 14, have grooved or knurled

surfaces 15 which engage the upper side of the edge portions of the sheet above the edge carrying portions 12 of roller 4, thus positively gripping these edge portions of the sheet between the two driving surfaces. 70 As before, the main central body of the sheet is not positively driven, but is supported during the bending operation upon the freely rotatable sleeve 8.

Claims:

75 1. In an apparatus for drawing sheet glass, a roller about which the sheet is deflected from one plane to another, the roller comprising separate end and central portions adapted to travel at different peripheral speeds.

80 2. In an apparatus for drawing sheet glass, a roller about which the sheet is deflected from one plane to another, the roller having a continuous cylindrical sheet-carrying surface, comprising separate end and central portions adapted to travel at different peripheral speeds.

85 3. In an apparatus for drawing sheet glass, a continuous cylindrical roller about which the sheet is deflected from one plane to another, comprising portions adapted to support and draw the edge portions of the sheet and a freely rotatable portion for supporting the main central portion of the sheet.

90 4. In an apparatus for drawing sheet glass, a roller about which the sheet is deflected from one plane to another, the roller comprising end portions for carrying the edge portions of the sheet, and a freely rotatable intermediate portion.

95 5. In an apparatus for drawing sheet glass, a roller about which the sheet is deflected from one plane into another, the roller comprising end portions for carrying the edge portions of the sheet, and a freely rotatable sleeve journaled on the central portion of the roller.

100 6. In an apparatus for drawing sheet glass, a roller about which the sheet is deflected from one plane into another, the roller comprising end portions for carrying the edge portions of the sheet, and a freely rotatable sleeve journaled on the central portion of the roller, and having a cylindrical sheet-carrying surface of the same diameter as the end portions.

105 7. In an apparatus for drawing sheet glass, a roller about which the sheet is deflected from one plane into another, the roller comprising end portions for carrying the edge portions of the sheet, and a freely rotatable sleeve journaled on the central portion of the roller, and roller bearings between the sleeve and roller.

110 8. In an apparatus for drawing sheet glass, a roller about which the sheet is deflected from one plane into another, the roller comprising end portions for carrying the edge portions of the sheet, and a freely rotatable sleeve journaled on the central portion of the roller, and roller bearings between the sleeve and roller.

115 120 125 130

ing the edge portions of the sheet, and a freely rotatable intermediate portion, in combination with a pair of driving rollers engaging the opposite faces of the edge 5 portions of the sheet.

9. In an apparatus for drawing sheet glass, a roller about which the sheet is deflected from one plane into another, the roller comprising end portions for carrying 10 the edge portions of the sheet, and a freely rotatable sleeve journaled on the cen-

tral portion of the roller, and having a cylindrical sheet-carrying surface of the same diameter as the end portions, in combination with a pair of driving rollers 15 engaging the opposite faces of the edge portions of the sheet.

Signed at Toledo, in the county of Lucas and State of Ohio, this 25th day of January, 1924.

JOSEPH. A. REECE.
